UNITED STATES PATENT OFFICE.

SAVILLE SMITH AND HERBERT LANGTON, OF PHILADELPHIA, PENNSYLVANIA.

SMOKE-CONSUMER.

1,131,280.

Specification of Letters Patent.

Patented Mar. 9, 1915.

Application filed June 2, 1914. Serial No. 842,427.

To all whom it may concern:

Be it known that we, SAVILLE SMITH and HERBERT LANGTON, citizens of the United States, residing at Philadelphia, in the county of Philadelphia and State of Pennsylvania, have invented certain new and useful Improvements in Smoke-Consumers, of which the following is a specification.

Our invention relates to new and useful improvements in furnace constructions and more particularly to the draft arrangements thereof, the primary object of our invention being the provision of an overhead draft, resulting in much more perfect combustion and consequent saving of fuel and avoidance of smoke.

More specifically, the object of our invention is to provide means for supplying air above the bed of the fire in the furnace from the front, back and sides, in such a manner that no forced draft will be required to insure perfect combustion of fuel and smoke.

A still further object of our present invention is to provide an additional supply of air at some point between the fire box and smoke stack of the furnace to insure complete combustion of all smoke. And a still further object of our invention is to highly heat the air supplied to the fire box in order to render the combustion still more perfect.

With these and other objects in view, our invention will be more fully described, illustrated in the accompanying drawings and then specifically pointed out in the claims which are attached to and form a part of this application.

In the drawings: Figure 1 is a central longitudinal sectional view taken through a boiler furnace of conventional type, showing our invention applied thereto; Fig. 2 is a top plan view of the interior of the furnace, the boiler being omitted to permit more clear showing of the air tubes employed, certain of these tubes being shown in horizontal section; Fig. 3 is a transverse sectional view taken on the line 3—3 of Fig. 2, looking in the direction of the arrows.

Corresponding and like parts are referred to in the following description and indicated in all the views of the drawings by the same reference characters.

In order to insure a clear understanding of our invention, we have illustrated it in connection with a conventional boiler furnace having front and rear walls 10 and 11,

a bridge wall 12, a front arch 13, fire pit 14, ash pit 15 and grate 16. Doors 17 and 18 provide access to the fire pit and ash pit, respectively, and the normal draft of the furnace is through the grate 16, as is usual in furnace constructions of this type.

As best shown in Figs. 1 and 2 of the drawings, the front arch 13 is hollow and has its rear end open. The rear portion of the front arch is divided longitudinally by a plurality of spaced partition walls 19 providing a series of air tubes 20 all opening at their rear ends into the fire pit and at their forward ends into a transverse chamber 21. Air tubes 22 lead from either side of this chamber 21 along the sides of the fire pit and over the top of the bridge wall, opening through the back wall 11 of the furnace as shown in Fig. 2.

Located at either side of the fire box and slightly above the forward arch 13, are air tubes 23 closed at their forward ends and having their inner faces perforated at 23' to admit air over the fire. These air tubes 23 extend at their rear ends over the top of the bridge wall, being located adjacent to the air tubes 22 and also opening through the back wall of the furnace. Located adjacent the bridge wall and transversely of the furnace, is a rear arch 24 provided centrally with a transverse partition 25 and having a central transverse chamber 26 communicating with forwardly and rearwardly extending passages 27 through which the air passes. Air tubes 28 lead from the ends of the central chamber 26 over the bridge wall and communicate at their outer ends through the back wall of the furnace, these tubes being located adjacent to the tubes 23.

As clearly shown in Fig. 1 of the drawings, the air tubes 22, 23 and 28 extend along the sides of the furnace, one above the other and after passing over the bridge wall, are directed downwardly and toward each other from the opposite sides of the furnace and then extended in parallel relation to the back wall. By this means, these tubes in themselves provide an air tube or passage 29 formed centrally along the bridge wall and terminating at its forward end in a forwardly converging chamber 30 opening directly over the back of the fire pit and immediately at the rear of the rear arch 25.

Vertically disposed air tubes 31 are located at either side of the furnace adjacent the rear end of the boiler 32 and are pro-

vided in their inner faces with draft openings 33. The lower ends of these tubes are extended at right angles as shown at 34 along the top of the air tubes 22 and also 5 open through the rear wall of the furnace.

The various air tubes above described may be formed of metal or any other suitable material and either as separate elements or as a built up structure formed 10 from plates connected by partition walls to provide the tubes. However, they will preferably be formed of brick or other suitable refractory substance in the manner shown in the drawings.

15 In operation, the ordinary draft of the furnace is sufficient to create a suction through the air tubes 22, 23, 28, 29 and 31, air being drawn in through the rear wall of the furnace and during its passage through 20 these tubes, being highly heated by the burning gases in the furnace. This highly heated air is then discharged through the draft passages 20 of the front arch, draft passages 27 of the back arch, draft openings 25 24 at the sides of the fire box, through the open forward end of the draft chamber 30 over the bridge wall, and through the draft openings 33 of the vertical draft tubes 31. It will be seen that in this manner, a supply 30 of highly heated air is furnished immediately above the bed of the fire in the fire pit 14 and that such air is supplied from all four sides of the fire pit. The currents of heated air thus supplied meeting each other 35 and the burning gases as they pass from the bed of the fire, insure practically perfect combustion of the fuel and of such gases. Furthermore, any unconsumed gases, during their passage through the furnace, are 40 later consumed by combination of the air entering the vertical draft tubes 31. Because of this, almost perfect combustion of the fuel, gases and smoke is obtained, resulting in great economy in fuel, absence of smoke 45 and high heating capacity. The consumption of the smoke, of course, preserves the boiler and its tubes, thereby lengthening the life of the furnace. Furthermore, with this draft arrangement, absolutely no forced 50 draft is necessary, the operation of the furnace being thereby cheapened and the amount of fuel required reduced.

It will of course be understood that, although we have illustrated this draft system in connection with one particular type 55 of furnace, it may be readily applied to furnaces of all types whether for locomotives,

stationary or marine boilers or boilers burning either coal or oil. We, therefore, do not wish to limit ourselves to the specific details 60 of construction disclosed in the drawings and described in the above specification as any changes, within the scope of the appended claims, may be made at any time, without in the slightest degree departing 65 from the spirit of our invention.

Having thus described the invention, what is claimed as new is:

1. In boiler furnace construction, the combination with a fire pit and bridge wall, 70 of an air tube opening out of the furnace at the rear and terminating at its forward end in a fan shaped enlargement at the front of the bridge wall, a rear arch disposed in front of the bridge wall and open at its 75 front and back for the passage of air from the fan shaped extension of the air tube, and a plurality of partition members in the arch.

2. In boiler furnace construction, the 80 combination with a fire pit and bridge wall, of an air tube opening out of the furnace at the rear and terminating at its forward end in a fan shaped enlargement at the front of the bridge wall, a rear arch disposed in 85 front of the bridge wall and open at its front and back for the passage of air from the fan shaped extension of the air tube, and a plurality of partition members in the arch, said members extending from front to 90 rear to form passageways.

3. In boiler furnace construction, the combination with a fire pit and bridge wall, 95 of an air tube opening out of the furnace at the rear and terminating at its forward end in a fan shaped enlargement at the front of the bridge wall, a rear arch disposed in front of the bridge wall and open at its 100 front and back for the passage of air from the fan shaped extension of the air tube, and a plurality of partition members in the arch, said members extending from front to rear to form passageways, certain of the 105 said members being broken away intermediate their length to provide communication between the passageways thus formed.

In testimony whereof we affix our signatures in presence of two witnesses.

SAVILLE SMITH. [L. S.]
HERBERT LANGTON. [L. S.]
